UNITED STATES PATENT OFFICE.

SOLOMON PRICE AND SOLOMON DAVIS, OF MELBOURNE, VICTORIA, AUSTRALIA,
ASSIGNORS TO SAMUEL PRICE, OF MELBOURNE, AUSTRALIA.

LOCK-DOWN MULTIPLE-COTTON-REEL HOLDER.

1,292,511.

Specification of Letters Patent. Patented Jan. 28, 1919.

Application filed February 15, 1917. Serial No. 148,784.

To all whom it may concern:

Be it known that we, SOLOMON PRICE and SOLOMON DAVIS, British subjects, and residents, respectively, of No. 50 Armstrong street, Middle Park, and No. 30 Russell street, Melbourne, both in the State of Victoria, Commonwealth of Australia, have invented certain new and useful Improvements in Lock-Down Multiple-Cotton-Reel Holders, of which the following is a specification.

This invention relates to a lock-down multiple reel holder for such as cotton reels, which has been designed for use mainly in clothing factories and like establishments, where it becomes necessary to hand out to the operatives a number of assorted reels of cotton or silk, for use in the manufacture of clothing, garments and other like articles, also the invention is applicable to sewing machines for supplying the cotton thereto, it taking the place of the single reel.

The invention will now be described aided by a reference to the attached sheet of drawings which illustrates the preferred form of the invention as it will be obvious that the multiple cotton reel holder may be made in other forms without departing from the object of our invention which is to secure or lock the reels of cotton on the holder in such a manner that they can only be removed by the person holding the key of the lock or fastening appliance.

Referring to the drawing, Figures 1 to 4 are drawn to about half actual size, while the remaining detail figures are about full size although we do not limit ourselves to making the reel holders to any particular size. In said drawings

Figure 1 is a top plan and

Fig. 2 a side view of the lock down reel holder, the latter figure showing it seated on a pedestal or stand.

Fig. 3 is a central sectional view on line *a*, *a* Fig. 1 and showing the key for locking the cover plate in position and the reel holder arranged on the pin of a sewing machine arm.

Fig. 4 an underside plan of the top or cover plate.

Fig. 5 a detail side view of the locking means attached to the underside of cover plate and showing part of the tubular or box key in dotted lines while

Fig. 6 is an underside plan of Fig. 5 but

showing the swivel catch or button in its locking position.

Fig. 7 is a central section of the upper part of the reel holder tubular column showing the side wall for retaining the catch or button and

Fig. 8 is a central section of the central tubular part of reel holder showing the means for locking the cover plate in position and the means of centering its lower part on a vertical pin.

The invention is constructed of a horizontal double plate disk A having a central tubular column A¹ secured to it and rotatable on a central pin B, said disk A also has say six or any desired number of vertical pins A² arranged in a circle and projecting upward at equidistant positions from its surface, the heads of said pins being soldered to the under surface of the upper plate and thus lying in the space between it and the lower plate as shown in Fig. 3, while supported loosely on the upper end of column A¹ and above the pins A² is a cover disk C whose distance above the lower disk suits the height of the several assorted cotton reels D when placed on said pins A² and secured thereon by the lock down cover C which is provided with a central key hole C¹.

The locking means between tubular column A¹ and cover C consist in providing within the tube, two depending catch pieces a¹—a¹ supported from top end of tube and so forming an oblong slot thereat (see Fig. 1) while attached to the underside of cover C is a descending bridge piece c¹ having a swiveling latch or button c² centered on its lower part at such a position that when its square or polygonal center stud c³, which is made secure to the said latch by screw nut and soldering, is turned by such as a tubular or box key E, the end parts of latch or button c² will pass to under the cheek pieces a¹ and so lock the cover C securely in position to prevent the removal of the reels D from their pins A². At the lower part of tube is a ferrule A³ to take the pin B, such ferrule being held in position by being secured to the bottom plate A and at top end to a cross piece a² secured in the tube A¹.

When the multiple reel holder is used to hold the cotton reels for a set of operatives at a table, then the pin B on which it rotates, is provided on a flanged pedestal or

- movable seating B^1 , Fig. 2, or when employed with a sewing machine, the reel holder is placed on the pin B provided on the sewing machine arm B^2 , Fig. 3.
- 5 Further, this appliance instead of being circular in plan may be square or polygonal with the reels arranged on a series of pins and locked thereon as aforesaid, or still, further, the reel pins A^2 may be arranged in 10 a straight line between the upper and lower parallel bars instead of the disk plates, and be centered on a pin as E on a seating or pedestal as before. The lock down holder may be constructed of wood or metal.
- 15 From the foregoing, it will be understood that our invention resides mainly in the provision of a lock down multiple reel holder of any description for use in such as clothing factories, and upon sewing machines, 20 and it will be obvious that locking means other than what is hereinbefore described and shown in the drawings may be employed.

Having now described our invention what 25 we claim as new and desire to secure by Letters Patent is,—

1. A lock down multiple reel holder consisting of a disk with a central tubular column rotatable on a stationary pin, said 30 disk being furnished with a number of vertical pins to take the cotton reels, an upper disk seated on top end of said central tubular column and providing with locking means consisting of a swiveling latch, the 35 ends of which pass under suitable cheeks in the tubular column, substantially as described and shown.
2. A lock down multiple reel holder consisting of a disk or lower plate having a 40 central tubular column and a ring of vertical pins combined with a disk or cover plate

having central hole to take a key and a suitable swiveling latch designed to engage the under edges of catch plates located in the tubular column substantially as described 45 and shown.

3. A lock down multiple reel holder of the type herein described furnished with a central hole in its lower part in combination with a pedestal or stand having a central 50 pin upon which the holder can rotate, a column fixed to and upstanding on the holder and being hollow in its upper portion, a cover disk adapted to be positioned over the top of the column, and means for 55 locking the cover disk on the column including two parts, an adjustable locking member and a keeper therefor, one of said parts being carried by the cover disk and the other being positioned inside the hollow upper 60 portion of the column, substantially as described and shown.

4. A lock down multiple reel holder comprising in combination a disk or plate, pins thereon to take the reels, a central tubular 65 column also thereon, a cover disk or plate adapted to be mounted on the tubular column, and locking means for securing the cover disk on the tubular column, said locking means including a locking member carried by and movable on the cover disk and a keeper for said locking member positioned 70 inside the tubular column.

In testimony whereof we have signed our 75 names to this specification in the presence of two subscribing witnesses.

SOLOMON PRICE.
SOLOMON DAVIS.
